United States Patent Office.

SAMUEL SIMPSON, OF WALLINGFORD, CONNECTICUT, ASSIGNOR
TO SIMPSON, HALL, MILLER & CO.

Letters Patent No. 90,596, dated May 25, 1869.

IMPROVED DIE FOR RAISING AND TRIMMING METAL.

The Schedule referred to in these Letters Patent and making part of the same.

To all whom it may concern:

Be it known that I, SAMUEL SIMPSON, of Wallingford, in the county of New Haven, and State of Connecticut, have invented a new Improvement in Raising and Trimming-Die for Sheet-Metals; and I do hereby declare the following, when taken in connection with the accompanying drawings, and the letters of reference marked thereon, to be a full, clear, and exact description of the same, and which said drawings constitute part of this specification, and repre-sent in—

Figure 1, a perspective view of the die as used for striking up metals, and in

Figure 2, a perspective view of the die, the auxil-
iary part shown in Figure 3, removed.

This invention relates to an improvement in the manufacture of sheet-metal ware, especially designed for the manufacture of ware preparatory to plating; that is, to the formation of disks for covers, dishes, &c.

Heretofore, this has been done by striking the metal into shape, and then trimming off the surplus metal around the edge. In circular work, this is usually done by placing the article on a revolving form, and trimming it by the application of a cutter thereto while so revolving; but in oval, or other than circular shapes, the trimming must be done by hand, and is a very difficult part of the work, the simplifi-cation of which is the object of my invention, which consists in forming the die in which the metal is struck up, in two parts, the principal part of which is of the exact form and size required for the article when complete.

The other and auxiliary part is an addition placed upon the top of the die, and corresponding in form to the upper edge of the die, so that the surplus metal is drawn into form, to be merely an extension of the article.

The follower is dropped or struck into the die in the usual manner; then, when the requisite number of articles have been struck up, the auxiliary part of the die is removed, and each of the articles suc-cessively replaced in the die and trimmed, the upper edge of the die serving as a guide to direct the cutter.

To enable others to make and use my invention, I will fully describe the same as illustrated in the accom-panying drawings.

A is the principal part of the die, the recess B being of the form and size required for the article to be produced.

C, the auxiliary part, is placed over and secured to the principal part of the die, the opening D, therein, corresponding exactly to the principal part A, as seen in fig. 1. In this condition the metal is placed upon and struck into the die by the follower in the usual manner, and when the requisite number of articles have been formed, then the part C is removed from the part A, leaving the part A as seen in fig. 2.

When the articles are each successively replaced in the die, the upper edge of the die serving as a guide, the cutter is passed around, trimming the article flush with the edge of the die, thus insuring the per-fection of the work at a single operation, and without other trimming.

Having fully described my invention,
What I claim as new and useful, and desire to se-
cure by Letters Patent, is—

In a die for raising sheet-metals, constructing the same in two parts, A and C, the part C removable from the part A, for the purpose set forth.

SAMUEL SIMPSON.
